FOOT MASSAGING AND VIBRATING DEVICE

Herbert E. Walters, San Francisco, Calif., assignor
to Wendell E. Kindley, Oakland, Calif., and
T. L. Hyde, The Dalles, Oreg.

Application December 7, 1948, Serial No. 63,923

8 Claims. (Cl. 128—46)

1

This invention relates to massaging and vibrating devices and particularly to a device adapted to massage the feet.

It is well known that skillful massaging of the feet aids the circulation of the blood in the legs thereby permitting the return to the venous system of the wastes of fatigue. Such massaging also has the effect of exercising and strengthening the muscles of the feet and contributes to the elimination of many common foot ailments. When massaging of the nature is performed manually, the desired results are obtained only after a strenuous and time consuming physical manipulation of the feet.

One of the objects of this invention is the provision of a foot massager which will effect mechanically a complete massaging of the feet in a few minutes.

Another object of the invention is the provision of a foot massager which will impart a beneficial vibrating motion simultaneously to both the metatarsal arch and the heel of the foot, thereby simulating the practiced manipulations of an experienced masseur.

Still another object of the invention is the provision of a mechanical foot massager of compact proportions, which may be automatically correctly positioned with respect to the body to insure beneficial results.

Other objects and advantages will be apparent from the specification and drawings.

In the drawings Fig. 1 is a plan view of the massager detached from its support and partially broken away and in section to show structure.

Fig. 2 is a sectional view of a portion of the massager as taken along lines 2—2 of Fig. 1.

Fig. 3 is a sectional view of a portion of the massager as taken along lines 3—3 of Fig. 1.

Fig. 4 is a sectional view of a portion of the massager as taken along lines 4—4 of Fig. 1.

Fig. 5 is a sectional view taken along lines 5—5 of Figs. 3 and 1, showing the spring and its associated mechanism.

Fig. 6 is a side elevational view of the massager along with its supporting structure and chair, several of the different positions of the massager being indicated in dotted lines.

Fig. 7 is an end elevational view of the structure shown in Fig. 6 except for the chair, which is omitted for clarity, and taken from the end of the structure opposite the chair.

Fig. 8 is a schematic diagram of the parallel-
ogram defined by the supporting structure of the
massager.

2

The mechanism of the massaging device is preferably supported within two box-like casings (Fig. 1), an outer casing generally designated 1 and an inner casing generally designated 2. The inner casing 2 is spaced from the outer casing 1 by means of vibration insulators 3 so that any undesirable mechanical vibrations created within the mechanism will not be transferred to the outer casing.

An electric motor 4 is positioned within the inner casing and is secured to one side of said casing by means of brackets 5 and bolts and nuts 6 and 7 respectively (Fig. 3). The shaft of the electric motor is provided with coaxial extension shafts 10, 11 on opposite sides of the motor and each is formed with an eccentric portion 13 adjacent each of the brackets 5 and spaced outwardly therefrom away from the motor. Connecting rods 14 are mounted on the eccentric portions of the extension shafts 10, 11, and axial movement of the connecting rods on extension shafts 10, 11 is prevented by washers 15, 16 on said shafts. A pulley 17 is secured on shaft 10 by key 18 and is adapted to drive a belt 19 for a purpose to be described.

Disposed within casing 2 and parallel to shafts 10, 11 is a driven shaft 21 (Fig. 4) having at one of its ends a pulley 22 keyed thereto by key 23 and adapted to be driven by belt 19. Shaft 21 is journaled in bearings 24 which in turn are secured to a channel-like carriage 25 by means of bolts 26 and nuts 27. The flanges on opposed sides of the channel 25 are apertured to slidably pass rods 28 on which rods the said carriage is supported for adjustable movement along the same. Rods 28 are rigidly secured at one of their ends as by welding to a wall of casing 2 and at their other ends they are secured to said casing by means of brackets 29 (Fig. 2).

Connecting rods 30 are mounted on eccentric portions 31 of shaft 21 in a similar manner as connecting rods 14 are mounted on eccentric portions 13 of shafts 10, 11.

Heel supports 35 are threadedly secured to the ends of connecting rods 14 and metatarsal supports 36 are threadedly secured to the ends of connecting rods 30 (Fig. 2). Inner casing 2 is apertured as at 37 to allow connecting rod 14 to pass through the same and outer casing 1 is apertured as at 38 for the same reason. Elongated slots 39, 40 are provided in casings 2 and 1 respectively at right angles to shaft 21 to allow connecting rods 30 to reciprocate relative to casings 1, 2, when the carriage 25 is moved along

rods 28. The web of carriage 25 is apertured as at 41 (Fig. 1) to allow connecting rods 30 to pass through the same.

As best seen in Fig. 2 when the user's foot is placed on the massager with the heel of the foot on the heel support 35 the metatarsal support 36 may be moved relative to the heel support by moving carriage 25 to accommodate whatever size of foot is to be massaged. The limits of travel of metatarsal support 36 are shown in Fig. 2 wherein the dot-dash lines indicate the metatarsal support and its associated mechanism in the position closest to the heel support while the position most remote from the heel support is shown in full line.

An effective arrangement of idler pulleys 45, 46 permits the carriage 25 to be moved along rods 28 to various positions while the mechanism is running. Idler pulley 45 is journaled on pin 47 which in turn is secured in boss 48 on a wall of casing 2. Boss 48 and washer 49 at opposite sides of the pulley prevent movement of pulley 45 axially along pin 47. Idler pulley 46 is journaled on a pin 52 carried on one end of lever 51. The lever 51 is pivotally connected to casing 2 adjacent the end of shaft 10 by means of pin 53 which pin is coaxial with shaft 10. The end of lever 51 opposite that end on which pulley 46 is journaled is connected to tension spring 54 which spring yieldably urges the pulley 46 against belt 19. Thus it is seen that the belt 19 which drives shaft 21 is opened out by means of pulley 45 while a predetermined tension is provided in the belt 19 by means of pulley 46 and spring 54. As shaft 21 is moved towards the motor shaft the tension in belt 19 which would otherwise relax is maintained automatically by the movement of pulley 46 towards belt 19 under the action of spring 54. The side of casing 2 adjacent the pulley 45 is provided with a relatively large opening 55 through which pulley 45 and belt 19 may project and also through which the mechanism in casing 2 may be reached for servicing when casing 1 is opened.

The connecting rods 14 and 30 are adapted to transmit a unique and very beneficial vibratory motion to the foot supports 35 and 36 and the method for accomplishing this motion will now be described.

The connecting rods 14, 30 are pivotally connected intermediate their ends to one of the ends of links 58, 59 respectively and links 58, 59 are in turn pivotally connected at their opposite ends to brackets 60, 61 respectively (Fig. 2). Brackets 60 are rigidly secured to a side of the casing 2 adjacent hole 37 and brackets 61 are rigidly secured to the web of channel-like carriage 25 adjacent holes 41. Thus it is seen that not only is a reciprocating motion imparted to connecting rods 14, 30 but also a swinging or oscillatory motion in direction transversely of the axis of the connecting rods 14, 30. It is readily apparent that the distance between supports 35, 36 is thus continuously changed although such change may be relatively small. It is also apparent that the arcuate motions of supports 35, 36 will never remain in phase because of belt slippage. As a result the foot is continually subject to changing forces in a direction longitudinally of the foot as well as reciprocating forces transversely of the foot. It has been found that the motions thus imparted to the foot are extremely beneficial and simulate to a great extent the practical manipulations of an experienced masseur.

For the purpose of moving carriage 25 to an adjusted position toward or away from the heel supporting assembly a handwheel 65 (Fig. 3) is provided on the outside of the outer casing 1 centrally of the heel supports 35. This handwheel 65 is rigidly secured to shaft 66 which in turn is rotatably secured in plate 67. Plate 67 in turn is rigidly connected to the casing 2 and serves to support a pinion 68 which is rigidly secured to shaft 66. Plate 69, is provided on the opposite side of pinion 68 from plate 67 and is secured to plate 67 by means of bolts 70. A hole is formed in plate 69 through which hub 71 of pinion 68 is positioned.

15 An elongated connecting rod 74 (Fig. 1) is disposed between plates 67, 69 adjacent one of its ends and is provided with a rack 75, the teeth of which are in mesh with the teeth of pinion 68. The opposite end of connecting rod 74 remote 20 from pinion 68 is rigidly connected to carriage 25 by means of brackets 76. Inner casing 2 is slotted at 73 to allow brackets 76 to pass through the same. Thus it is seen that rotation of handwheel 65 will cause movement of carriage 25 to 25 a position toward or away from the heel supporting assembly. An indicating hand 77 may be carried by handwheel 65 and indicia 78 may be marked on the outer casing 2 so that the handwheel may be rotated to a position indicating 30 the shoe size of the user before the feet are placed on the massager, thus providing an effective means of obtaining the proper position of metatarsal support 36 relative to heel support 35.

Thus it is seen that the mechanism which 35 transmits the vibrations to the foot supports 35, 36 is compact and neat in appearance. The foot supports 35, 36 and the handwheel 65 are the only members that are not entirely within the casing 1. To provide ready access to the mechanism 40 within the casings a door 79 (Fig. 2) may be formed flush with the outer wall of casing 2 and a locking device such as shown at 80 may be employed to securely close the entire unit.

An important feature of the present invention 45 resides in the supporting means employed to position the massaging device relative to a chair on which the user is seated. Referring to Figs. 6, 7 it is seen that a chair 81 of comfortable proportions preferably made of tubular steel is adapted 50 to be used in conjunction with the massager so that the proper proportions between the chair and the massager and the proper angle of inclination of the foot supports 35, 36 is insured at all times. A platform 82 is positioned on horizontal longitudinal extensions 83 of the front legs of the chair and said extensions are supported by legs 84. Cross piece 85 (Fig. 7) serves 55 to space apart the extensions 83 and is provided with a hinge 86 centrally between the extensions 83 for hingedly securing center support 87 of the massager.

The center support 87 preferably extends generally horizontally away from the platform 82 60 and is bent back upon itself and extends generally vertically but inclined somewhat towards the chair 81 and is then bent back approximately at right angles to the generally vertical portion and is hingedly secured to the massager by hinge 88.

70 In addition to the center support 87 the massager is secured relative to chair 81 by outer supports 90. These outer supports are, at their lower ends, continuations of extensions 83 and extend horizontally away from platform 82 and 75 are bent back upon themselves in a similar man-

ner as center support 87. However, the outer supports are provided with a hinge 91 intermediate the platform 82 and the massager for a purpose to be described. The outer supports 90 extend upwardly from hinge 91 and are inclined to the same angle as center support 87 and are bent at right angles adjacent their upper end and secured to casing 1 by means of elbows 92.

Integrally secured to the inner side of casing 1 are bosses 93 provided with holes 94 which holes register with holes 95 in elbows 92 (Fig. 3). Bolts 96 are threadedly secured in holes 95 and the casing 1 is rotatably mounted on the shanks of bolts 96 by means of bosses 93.

The supporting structure above described is proportioned to create a parallelogram, the corners of which are defined by hinge 88, hinge 86, hinge 91 and bolt 96. Thus, when the massager is moved from the full line position to the dotted line position in Fig. 6 the casing 1 remains at all times inclined to the same angle to the vertical. By virtue of this parallelogram the user may seat himself on the chair 81, place his feet on the supports 35, 36 and push on the massager until a comfortable position is attained without moving his feet on the supports 35, 36. A diagrammatic arrangement of the parallelogram is shown in Fig. 8.

For the purpose of providing a predetermined resistance to this movement of the massager, springs 98 are provided within the casing 1 and are installed in a manner which will now be described.

Positioned on the inner sidewall of casing 1 are bosses 99 which are similar to bosses 93 (Fig. 5). One end of each spring 98 is pivotally connected to boss 99 by means of pin 100 and the other end of spring 98 is pivotally connected to arm 101 which arm is apertured adjacent one of its ends to receive the spring 98. The opposite end of arm 101 is rigidly secured to the head of bolt 96 and thus becomes in effect a rigid extension of support 90, inasmuch as bolt 96 is threadedly secured to elbow 92. As best seen in Fig. 8 which is a schematic arrangement of the parallelogram, the spring 98 becomes extended when the massager is pushed away from the chair 81.

To insure a smooth movement of the massager at all points in its travel a shock absorber 103 is provided under the platform 82. An elongated upwardly extending link 104 is pivotally connected at its lower end to the outer end of the operating arm 105 of the shock absorber and is pivotally connected at its upper ends to hinge 88. A stop lug 106 may be rigidly secured to the link 104 above the platform 82 and lug 107 similarly secured to link 104 under the platform so that the travel of the massager may be limited as desired.

It is to be understood that the detailed drawings and descriptions are not to be considered restrictive of the invention, but merely illustrative thereof.

I claim:

1. In a foot massaging device, a housing, a pair of spaced foot engaging elements within said housing projecting from a side of said housing for engaging each of the feet of a person, a power actuated mechanism and motor therefore within said housing connected with said elements for vibrating said elements, a supporting base, pairs of parallel links, means pivotally connecting the links of said pairs respectively to each other at their opposite ends and with said supporting base support and said housing to permit swing-

ing of said housing to different positions and for holding said housing against rotation about its respective axes during such movement whereby said elements will face in substantially the same direction during said swinging, a spring connected with said housing and with one of said links for yieldably holding said housing at one end of its swinging movement, and a stop for limiting the motion of said links at said one end of said movement.

2. In a foot massaging device, a housing, a pair of spaced foot engaging elements within said housing projecting from a side of said housing for engaging each of the feet of a person, a power actuated mechanism and motor therefore within said housing connected with said elements for vibrating said elements, a supporting base, pairs of parallel links, means pivotally connecting the links of said pairs respectively to each other at their opposite ends and with said supporting base support and said housing to permit swinging of said housing to different positions and for holding said housing against rotation about its respective axes during such movement whereby said elements will face in substantially the same direction during said swinging, a spring connected with said housing and with one of said links for yieldably holding said housing at one end of its swinging movement, and a stop for limiting the motion of said links at said one end of said movement, said support including a seat for a person and said elements being at the side of said housing facing generally toward said seat.

3. In a foot massaging device having a pair of spaced sole engaging elements adapted to engage the sole of each foot at the heel and metatarsal portions respectively, a pair of spaced shafts supported for rotation, a pair of eccentrics on each of said shafts and a rod connecting each of said eccentrics with said elements respectively with the eccentrics on one of said shafts being connected with the elements adapted to engage the heel portions of said soles and with the eccentrics on the other shaft being connected with the elements adapted to engage the metatarsal portions whereby said elements will be caused to reciprocate simultaneously upon rotation of said shafts, a stationary support adjacent each of said rods and a link pivotally connected at its ends with each rod and the support adjacent thereto for causing oscillation of each rod in a plane disposed longitudinally of the foot and element thereon upon reciprocation of said elements, and means for rotating said shafts.

4. In a foot massaging device having a pair of spaced sole engaging elements adapted to engage the sole of each foot at the heel and metatarsal portions respectively, a pair of spaced parallel shafts, an inner housing enclosing said shafts, a carriage on which one shaft of said pair is rotatably supported for bodily movement toward and away from the other shaft of said pair, means supporting said carriage within said inner housing for said bodily movement, means supporting the other shaft of said pair in a fixed position within said housing and for rotation about its axis, a pair of eccentrics on each of said shafts, a rod connecting each eccentric with said elements respectively, a motor connected with one of said shafts for rotating the same, a pulley on each shaft and a belt connecting said pulleys for causing simultaneous rotation of said shafts, an outer housing, means supporting said inner housing spaced within said outer housing with said rods extending through one of the walls of said outer

housing and with said elements outside said outer housing.

5. In a foot massaging device having a pair of spaced sole engaging elements adapted to engage the sole of each foot at the heel and metatarsal portions respectively, a pair of parallel spaced shafts supported for rotation, a pair of eccentrics on each of said shafts and a rod connecting each of said eccentrics with said elements respectively with the eccentrics on one shaft of said pair being connected with the elements adapted to engage the heel portions of said soles and with the eccentrics on the other shaft being connected with the elements adapted to engage the metatarsal portions whereby said elements will be reciprocated upon rotation of said shafts, a pulley on each of said shafts, an endless belt extending over said pulleys for causing simultaneous rotation of said shafts upon rotation of one of them, power means connected with one of said shafts for rotating the same, means supporting said one shaft and the eccentrics, rods and elements connected therewith for bodily movement toward said other shaft, means for so moving said one shaft, and automatic belt take-up means in engagement with said belt for automatically maintaining the same under tension at all times.

6. In a foot massaging device that includes a seat for a person and a mechanical foot massager provided with sole engaging elements projecting from one side thereof, means supporting said massager and said seat for bodily movement of said massager as a unit and said seat respectively in a direction toward and away from each other to different distances under the influence of pressure applied by said feet against said elements whereby said one side will be held in a fixed position relative to the axis of said massager during said bodily movement.

7. In a foot massaging device that includes a

seat for a person and a mechanical foot massager provided with sole engaging elements projecting from one side thereof, means supporting said massager and said seat for bodily movement of said massager as a unit and said seat respectively in a direction toward and away from each other to different distances under the influence of pressure applied by said feet against said elements whereby said one side will be held in a fixed position relative to the axis of said massager during said bodily movement, said means including links pivotally connected to said massager.

8. In a foot massaging device that includes a seat for a person and a mechanical foot massager provided with sole engaging elements projecting from one side thereof, means supporting said massager and said seat for bodily movement of said massager as a unit and said seat respectively in a direction toward and away from each other to different distances under the influence of pressure applied by said feet against said elements whereby said one side will be held in a fixed position relative to the axis of said massager during said bodily movement, said means including links pivotally connected to said massager, and a spring yieldably resisting movement of said massager in a direction away from said seat.
